INVENTOR:

Moses P. Farnham

United States Patent Office.

MOSES P. FARNHAM, OF JANEVILLE, WISCONSIN, ASSIGNOR TO HIMSELF
AND DANIEL P. FARNHAM.

Letters Patent No. 63,150, dated March 26, 1867.

IMPROVEMENT IN GRATES FOR STOVES.

The Schedule referred to in these Letters Patent and making part of the same.

TO ALL WHOM IT MAY CONCERN:

Be it known that I, Moses P. FARNHAM, of Rock county, and State of Wisconsin, have invented a new and useful Improvement in a Supplemental Fire-Box for Stoves and Furnaces; and I do declare the following to be a full, clear, and exact description thereof, reference being had to the accompanying drawings, and to the letters of reference marked thereon.

The nature of my invention consists in making a movable or supplemental fire-box, of peculiar construction, to set inside a stove fire-box, and into the space in the top of a stove-plate, in place of a boiler, and suspending it by a flanch around its upper and outer edge, and having a movable bottom or grate that may be raised to different points of bearing to bring the fire nearer to or more distant from the articles to be cooked, or for other purposes; which grate rests on bearings, and may be tilted or tipped edgewise sufficiently to precipitate ashes, coals, &c., from its surface when desired; which general arrangement saves a great amount of fuel, and also avoids heating the stove and rooms where the stove is located.

The same letters in each figure represent the same part in the accompanying drawings.

Figure 1 is a view of the fire-box, cut vertically, showing a series of bearings, on which the lower grate sets at different points; also the upper grate above the flue, and the manner of its suspension inside the fire-box.

Figure 2 is a top view of the grate, with the pivots or axes that rest on the bearings, shown in figs. 1 and 3.

Figure 3 is a fire-box, broken away, showing the bearings for the pivots; also a grate tilted edgewise, to dump the ashes, cinders, coal, &c., into the stove below.

Figure 4 is a top view of a fine grate shown in fig. 1, and prevents the smoke from coming into a room when articles are removed from the top of the fire-box.

Figure 5 is a hook by which to move the grate.

A, in figs. 1, 2, and 3, is my supplemental fire-box, while B B B, in figs. 1, 2, and 3, serve as bearings for the axes *a a a* of the grate, the grate having a loop or aperture, D', for the hook F, fig. 5, by which the grate is handled in placing it on the different bearings, as needed in bringing the fire of coal or other combustible material nearer to the articles to be cooked or heated. Also the grate has three axes *a a a*, and corresponding sets of bearings. The bearings for the axes are not necessarily placed equidistant, it being better to place two of them apart, as *a* to *a'*, in fig. 2, which allows the grate to be tipped or tilted, as shown in fig. 3, which precipitates ashes or refuse matter into the fire-box of the stove. The flanch *b*, figs. 1 and 3, rests on the stove-plate, and keeps the supplemental fire-box from dropping into the fire-box proper of the stove, while the hook *c c c*, attached to the fine fire-grate E, serves to support this grate above the fire and above the flue G; and the slide H serves to close the flue wholly or in part, as may be desirable.

My supplemental fire-box, suspended inside a stove or furnace fire-box, is light, cheap of construction, and saves a large percentage of fuel, and heats apartments in which a stove or furnace is located but a small degree compared with a fire for cooking, &c., in an ordinary stove, which is important in hot weather, and can be used for most of the ordinary domestic purposes.

What I claim as my invention, and desire to secure by Letters Patent, is—

1. The supplemental fire-box A, for stoves and furnaces, having a movable bottom or grate, D, that may be placed on different bearings B, substantially as and for the purposes described.
2. The general arrangement of a supplemental stove fire-box, with grate D, bearings B, flue G, fine grate E, when the whole are constructed and arranged substantially as and for the purposes described.

MOSES P. FARNHAM.
